UNITED STATES PATENT OFFICE.

DAVID SCHAFER AND PETER E. LYNCH, OF PAWTUCKET, RHODE ISLAND.

TOOL FOR HANDLING VALVE SPRINGS OF AUTOMOBILES.

Application filed October 31, 1922. Serial No. 598,093.

To all whom it may concern:

Be it known that DAVID SCHAFER and PETER E. LYNCH, both citizens of the United States, residing at Pawtucket, in the county of Providence and State of Rhode Island, have invented certain new and useful Improvements in Tools for Handling Valve Springs of Automobiles, of which the following is a specification.

Our invention relates to improvements in tools for handling valve springs of automobiles, and the purpose of our invention is to provide a device by which the valve spring of an automobile may be quickly and easily compressed and after compression held in that condition for its ready application to the engine of an automobile.

We accomplish this purpose by the device shown in the accompanying drawings, in which—

Figure 1, is a plan view of our invention.
Figure 2, a vertical view of the same.

Figure 3, a cross-section of a portion of our device together with an elevation 25 of the holding clip.

Figure 4, a side view of the spring compressed and held by the clip, and

Figure 5, a detail of the locking apparatus for holding the spring when compressed.

The same parts are referred to by the same letters throughout the various views.

In Figure 1, A—A is a frame, preferably of metal, channeled or slotted longitudinally, as shown by G, in Figure 1.

The side members of the frame adjacent to the channel or slot G are of substantially rectangular cross-section, as shown best in Figure 3.

At the extremities of the device are lugs 40 perforated so that the entire device may be bolted securely to a bench or wall. Integral with the frame work and projecting upon one side thereof is the member B, and to this member B is pivoted the hand lever F—f by means of the pin or bolt E. This lever is itself slotted near H the middle portion thereof, as shown at t, in Figure 1, so as to form a guide for the stud r connected with the removable jaw D' of the device, as hereinafter described.

Integral with the frame A—A and at one end thereof is the fixed jaw D, seen in elevation in Figure 2.

Our device is also provided with the removable jaw D' shown in Figures 1 and 2, this movable jaw having fixed thereon the stud r, said stud projecting so as to slidably fit the slot t, in the hand lever F—f. This movable jaw D', slides easily upon the face of the frame work A—A which is toward the spectator in Figure 1, and integral with the stud r is a projecting lug which carries the movable jaw D' and slidably fits the slot G of the frame A—A, the stud r being fastened at one end to said lug, and projecting at the other end upon the side farthest from the spectator, in Figure 1, and slidably fitting into the slot in the hand lever F—f. It will be noted 70 that the jaws D—D' have their inner faces not strictly parallel but are slightly converging at their outer ends. This is in order to prevent the enclosed spring S, Figure 2, from slipping outward when compression thereof is being made.

It will be seen by Figure 1, that one side of the frame work A—A forms a rack C, projecting at right angles to the plane of the movable jaw; and integral with said movable jaw is the member X which is in substance a frame work carrying a pawl to engage the rack aforesaid. The member X is best shown in detail in Figure 5 in which X represents the body; L a rod or 80 plunger provided with a handle h' for rotating the same and terminating at its lower end in a bevelled or sharpened end L'—l adapted to fit the teeth of the rack C. The member X has a rectangular opening there- 85 in and at that part of the rectangular opening nearest the rack C there is a V shaped depression, as shown at V in Figure 5.

The plunger L is provided with a pin p at that part of the plunger adjacent to V, 95 and a spiral spring n normally operates to keep the plunger L, with its extremity L', in engagement with the rack C. By means of the bevelled face l at the lower extremity of the plunger L, the movable jaw D', can 100 be moved readily by means of the handle of the lever arm F—f in the direction which brings the jaws together, but by operation of the spring n, the movable jaw cannot be moved in the reverse direction until released by the plunger L. A quarter revolution of this plunger L by means of the handle h' through the agency of the pin p

and the V shaped depression V raises the plunger L, as shown by the dotted lines in Figure 5, thus disengaging the movable jaw from the rack, and permitting it to slide backward by means of the lever arm F-f. It will also be seen by an inspection of Figure 5 that when the plunger L is turned a complete quarter circle, the pin p will be in the position shown by the dotted lines p', and the plunger L will remain in that position, the pin p resting upon the flat surface of the rectangular opening in the member X adjacent to V until restored to its normal position by the reverse movement of the plunger L.

As shown by Figures 3, the inner corners of the side members A-A are beveled as shown at a, thus forming a seat for the spring S.

When the spring S has been compressed, as shown at S' in Figures 1 and 4 it is essential that it should be retained in that position for removal from our device and insertion to its place in the engine. We provide for this by the clip shown in Figures 3 and 4. This clip consists of a handle J with opposed longitudinal side members K-K bent at their outer ends so as to securely hold the spring together with the usual washer W. It is a very easy matter when the spring is held in compression, as shown at Figure 1, to attach the clip K-K. The clip with its enclosed spring may then be easily moved from the holding frame by releasing the movable jaw, and may be readily inserted in its proper place in the engine. A quick pull on the handle J disengages the clip and the spring is thus left in proper position.

From the foregoing description it will be seen that the advantages of our invention are that the spring has a suitable bed to rest upon when placed in the frame work so that it will not readily roll off or be detached therefrom. Also the difficulty met with in many spring compressors, of the spring jumping or flying out when the compression is slight, is overcome by our feature of making the jaws convergent at their outer ends.

Another feature is that the plunger L with its handle h' is in close proximity to the lever arm F-f and remains so throughout the travel of the movable jaw. As a result of this, both the handle h' and the handle F may be operated at the same time by one hand only of the operator, leaving the other hand free to hold the spring in place and apply the clip; while the operation of the plunger L with the spring n, the pin p and the V-shaped depression V, furnishes a simple and effectual means of retaining the movable jaw in engagement or out of engagement with the rack c as the operator may desire.

Having now described our invention what

we claim and desire to secure by Letters Patent is—

1. In a device for handling valve springs for automobile engines, a longitudinally slotted frame; a jaw fixed thereon; a movable jaw sliding upon one face of said frame, means for operating said movable jaw connected through said slot, and means for holding said movable jaw in a fixed position with reference to said frame, substantially as described.

2. In a device for handling valve springs for automobile engines, a longitudinally slotted frame having a rack upon one of the outside faces thereof; a jaw fixed upon said frame; a second jaw slidably mounted on said frame, said jaws being slightly convergent at their outer ends; a stud r fixed to said movable jaw and sliding in the slot in said frame; a member B attached to said frame; a slotted lever handle pivoted upon the member B and slidably holding the stud r, and serving to operate the movable jaw aforesaid, and means working in conjunction with said rack and movable jaw for holding the latter in any desired position, substantially as set forth.

3. In a device for handling valve springs for automobile engines, a longitudinally slotted frame having a rack upon one of the outside faces thereof; a jaw fixed upon said frame; a second jaw slidably mounted on said frame, said jaws being slightly convergent at their outer ends; a stud r fixed to said movable jaw and sliding in the slot in said frame; a member B attached to said frame; a slotted lever handle pivoted upon the member B and slidably holding the stud r, and serving to operate the movable jaw aforesaid; a member X integral with said fixed jaw and situated adjacent to the rack aforesaid, and having a transverse opening therethrough provided with a V shaped depression in the floor of said opening; a handled plunger sliding in said member X, and having its inner end bevelled so as to engage said rack; a spiral spring surrounding said plunger and acting to normally keep said plunger engaged with said rack by means of a pin projecting from each side of said plunger; and a second pin fixed in said plunger, and fitting with the V shaped depression aforesaid; said plunger by a partial turn of the handle thereof operating to disengage itself from the rack aforesaid, thus releasing the movable jaw, substantially as set forth.

4. In a device for handling valve springs for automobile engines, a frame, a jaw fixed upon said frame, a laterally projecting member carried by said frame, a lever pivotally attached to said member, a jaw slidably engaging said frame operatively connected to said lever, and means carried by said slideable jaw co-operating with said frame for

permitting free movement of said jaw in one direction only.

5. In a device for handling valve springs for automobile engines, a frame having a longitudinally extending rack formed thereon, a jaw fixed upon said frame, a laterally projecting member carried by said frame, a lever pivotally attached to said member, a jaw slidably engaging said frame operatively connected to said lever, and a plunger

carried by said slidable jaw cooperating with said rack for permitting free movement of said jaw in one direction only.

In testimony whereof we affix our signatures in presence of two witnesses.
